HANDED CARTONS

Kenneth T. Butterly, Kalamazoo, Mich., assignor to
Sutherland Paper Company, Kalamazoo, Mich.,
Application July 6, 1954, Serial No. 441,294
9 Claims. (Cl. 229—52)

This invention relates to handled cartons, including collapsible handled cartons.

The main objects of this invention are:

First, to provide a collapsible carton having a handle formed integrally therewith and one which may be formed of an integral blank without requiring the use of additional stock over what would be required if the handle were not included.

Second, to provide a handled carton which may be quickly erected and the handle adjusted to collapsed or carrying position.

Third, to provide a carton having these advantages which is simple, and economical to produce and the parts are securely retained when in erected position.

Further objects relating to details and economies of the invention will appear from the description to follow. The invention is defined and pointed out in the claims.

A preferred embodiment of the invention is illustrated in the accompanying drawing, in which:

Fig. 1 is a front perspective view of the carton embodying my invention in closed position and with the handle collapsed.

Fig. 2 is a front perspective view with the cover open, the handle being shown in one position with the closure flaps closed.

Fig. 3 is a fragmentary front perspective view showing the handle in another of its adjusted positions preliminary to the closing of the cover.

Fig. 4 is an enlarged fragmentary perspective view of the cover in closed position showing the relation of the handle thereto.

Fig. 5 is a fragmentary sectional view illustrating further details of the engagement of the handle.

Fig. 6 is a plan view of the blank in the flat or extended position.

Fig. 7 is a side view of the collapsed carton.

Fig. 8 is a fragmentary side view showing portions of the opposite side of the collapsed carton from that shown in Fig. 7.

Fig. 9 is a bottom view of the erected carton.

In the description and the claims I use the terms front, rear and end walls for convenience in the description and defining the relation of the parts without limitation as to relative dimensions and the shape of the carton.

In the accompanying drawing I have illustrated my invention as embodying a front wall 1, rear wall 2, and end walls 3 and 4 disposed in alignment in the blank and hingedly connected by the scores 5. The glue flap 6 is hingedly connected to the rear wall 2, by the hinging score 7. This glue flap, or sealing flap 6 is lapped on the wall 4 and adhesively secured thereto.

This results in a tubular structure which may be erected by pressure on the opposed edges of the collapsed structure. The self-erecting bottom illustrated is substantially that shown in my Patent No. 2,677,494 issued May 4, 1954, and comprises bottom members 8 hingedly connected to the bottom edges of the front and rear walls 1 and 2 by the scores 9, 9 and triangular bottom members 10 hingedly connected to the end walls by the scores 11, the members 10 being provided with hinging flaps 12 connected to the bottom members 10 by the diagonally disposed scores 13. The flaps 12 are adhesively secured to the adjacent bottom members 8. The edges of the bottom members 8 are provided with coacting interlock-

2

ing tongues 14 and 15. It should be understood that other forms of bottoms might be employed.

The parts heretofore described are substantially those disclosed in my said patent.

5 The cover 16 is hingedly connected to the upper edge of the rear wall 2 by the hinging score 17 and is provided with a tucking flap 18 hingedly connected to its swinging edge by the score 19. The end wall 3 has a closure flap 20 hingedly connected thereto at 21, while the end wall 10 4 has a closure flap 22 hingedly connected thereto at 23. The closure flap 20 has a handle 24 extending from its swinging edge and hingedly connected thereto by the diagonal hinging score 25. This handle 24 is strap-like and is provided with a laterally projecting retaining lug 26 at 15 its swinging end and desirably has a curved end 27. The end portion of the handle is cut from the flap 20 leaving a non-functional recess 28 therein. This, however, does not affect the utility of the flap. A slit 29 is formed at the juncture of the flap 20 with the wall 3 and has downwardly diverging or angled ends 30 facilitating the engagement of the handle with the slit.

It will be noted by a reference to Fig. 6 that the handle is formed, without requiring any additional stock, that is it is within the confines of a sheet of necessary 25 dimension to form the other parts. An inner-container or liner 31 is inserted in the carton as illustrated in Fig. 2, transparent material being illustrated.

After the container has been filled, the closure flaps 20 and 22 are folded inwardly as shown in Fig. 2. The handle is then folded or positioned outwardly by folding on the hinging score 25 to the position shown in Fig. 3. The cover is then closed and the tucking flap inserted between the front wall and the forward edges of the closure flaps which are beveled at 32 to facilitate this. Slits 33 are formed at the ends of hinging score 19 to permit the cover to close relatively flat upon the end flaps and over the inner end of the handle. The handle is scored at 34 and 35, the score 34 permitting the handle to fold over the adjacent edge of the cover, and the score 35 35 facilitating the insertion of the handle through the slit 29 and engagement of the lugs 26 thereof with the hinged portion connecting the flap 20 with the end wall 3. With an end portion of the handle inserted in the slit, the portion 36 extending beyond the score 35 may 40 be telescoped into the carton as shown by the dotted lines in Fig. 1, so that the handle lies flat upon the cover. In this position the handle does not interfere with the stacking of the cartons and at the same time may be quickly adjusted to using position by grasping and pulling upwards thereon.

50 To permit compact collapsing the cover is provided with a notch 37 receiving the portion 36 of the handle when the handle is completely collapsed. The handle is well anchored to the carton and even if its end 36 should become disengaged its other end is securely connected to the carton and the carton and the handle may be used as a supporting strap. However, such breaking is not likely to occur as the load on the handle is well distributed.

60 My invention is designed to be embodied in cartons formed of cardboard, or fibre board, such as is commonly used in commercial cartons. I have illustrated and described my invention in a practical commercial embodiment therefor. I have not attempted to illustrate or describe other embodiments or adaptations as it is believed this disclosure will enable those skilled in the art to embody or adapt my invention as may be desired.

Having thus described my invention, what I claim as new and desire to secure by Letters Patent is:

70 1. A collapsible handled carton formed of an integral cut and scored blank comprising hingedly connected front, rear and end walls having collapsibly associated bottom

members, a cover hingedly connected to the rear wall and having a tucking flap on its swinging edge, top closure flaps hingedly connected to the upper edges of the end walls to be positioned within the cover, there being a slit having angled ends at the juncture of the end of one of said flaps with its end wall, the other of said flaps having a handle extending from its inner end and connected thereto on a diagonal hinging line, said handle having laterally projecting retaining lugs at its outer end and having transverse scores spaced to correspond to the width of the carton so that the handle may be folded outwardly over the closure flap to which it is joined, and the cover closed and the handle folded over the cover and its end inserted in said slit with its lugs retainingly engaged at the ends thereof and the handle collapsed under the closed cover, the cover having a notch in its edge adjacent said slit and aligned therewith to receive said handle.

2. A collapsible handled carton formed of an integral cut and scored blank comprising, hingedly connected front, rear and end walls having collapsibly associated bottom members, a cover hingedly connected to the rear wall and having a tucking flap on its swinging edge, top closure flaps hingedly connected to the upper edges of the end walls to be positioned within the cover, there being a slit having angled ends at the juncture of the end of one of said flaps with its end wall, the other of said flaps having a handle extending from its inner end and connected thereto on a diagonal hinging line, said handle having laterally projecting retaining lugs at its outer end, said handle being foldable outwardly over the closure flap to which it is joined over the cover and its end inserted in said slit with its lugs retainingly engaged therein.

3. A carton comprising, front, rear and end walls, a cover hingedly connected to the rear wall, top closure flaps hingedly connected to the upper edges of the end walls to be positioned within the cover, there being a slit at the juncture of the end of one of said flaps with its end wall, the other of said flaps having a handle extending transversely therefrom and connected thereto for adjustment to an overlying position to project from beneath the end of the cover, said handle having a retaining lug at its outer end and having transverse scores spaced to correspond to the width of the carton so that the handle may be disposed outwardly between the flap to which it is joined at the cover and folded over the cover and its end inserted in said slit with its lug retainingly engaged at the ends thereof and the handle thus engaged collapsed upon the closed cover, the cover having a notch in its edge adjacent said slit aligned therewith to receive said handle.

4. A carton comprising, front, rear and end walls, a cover hingedly connected to the rear wall to be opened and closed, top closure flaps hingedly connected to the upper edges of the end walls to be positioned within the cover, there being a slit at the juncture of the end of one of said flaps with its end wall, the other of said flaps having a handle initially extending transversely therefrom and connected thereto for adjustment outwardly between the closure flap to which it is attached and the cover and around the adjacent end edge of the cover to a position overlying the cover when the cover is closed, said handle having a retaining lug at its outer end engageable through said slit with the handle disposed outwardly between the flap to which it is joined and the cover and folded over the cover and its end inserted in said slit with its lug retainingly engaged in said slit.

5. A carton comprising, front, rear and end walls, top closure flaps hingedly connected to the upper edges of the end walls, a cover closable over said flaps, there being a slit at the juncture of one of said flaps with its supporting end wall, the other of said flaps having a handle extending from the inner end thereof and foldable outwardly and positioned between the cover and the flap to which it is connected, said handle being foldable around

the end edge of the cover adjacent the flap to which the handle is attached and over the cover with its swinging end being retainingly engageable in said slit, said handle having longitudinally spaced scores of a width corresponding to the width of the carton so that the handle may be collapsed thereon when its swinging end is so engaged.

6. A carton comprising, front, rear and end walls, top closure flats hingedly connected to the upper edges of the end walls, a cover closable over said flats, there being a slit at the juncture of one of said flats with its supporting end wall, the other of said flats having a handle extending from the inner end thereof and foldable outwardly and positioned between the cover and the flap to which it is connected, said handle being foldable around the end edge of the cover adjacent the flap to which the handle is attached and over the cover with its swinging end being retainingly engageable in said slit.

7. A carton comprising, four walls and a bottom, top closure flaps hingedly connected to opposed walls, and a cover hingedly connected to one of the other pair of walls to close over said closure flaps, one of said flaps having a handle initially extending transversely from the swinging end thereof and connected thereto by a diagonal score facilitating the adjustment to the handle to approximately at right angles to its transverse position and to a superimposed position relative to the flap and an underlying position relative to the cover and around the adjacent end edge of the cover when closed, said handle being transversely scored in alignment with said adjacent edge of the closed cover to facilitate the adjustment of the handle in overlying relation to the closed cover, said handle having a laterally projecting portion on its swinging end lockingly engageable with a portion of the carton opposite that having the said handle carrying flap.

8. A carton comprising, four walls and a bottom, top closure flaps hingedly connected to opposed walls, a cover hingedly connected to one of the other pair of walls to close over said closure flaps, one of said flaps having a handle initially extending transversely from the swinging end thereof and connected thereto by a diagonal score facilitating the adjustment to the handle to approximately at right angles to its transverse position and to a superimposed position relative to the flap and an underlying position relative to the cover and around the adjacent end edge of the cover when closed, said handle being transversely scored in alignment with said adjacent edge of the closed cover to facilitate the adjustment of the handle to an overlying position relative to the closed cover, and means for connecting the swinging end of the handle to the side of the carton opposite that having the said handle carrying flap.

9. In a carton, a plurality of walls, a bottom, a closable cover, a closure flap hingedly connected to the upper edge of one of said walls and positioned within the cover when closed, and a handle integral with the flap and initially extending transversely of one of the opposed side edges of the flap, the flap and handle having a diagonal folding score therebetween to facilitate adjustment of the handle from the initial transverse position to a position overlying the flap, the handle extending outwardly between the flap and the cover and around the edge of the cover adjacent the flap and over the cover when the cover is closed.
